6 Claims. (Cl. 66—1)

My invention relates to the manufacture of knitted articles, such as ladies' silk stockings, and the object of the present invention is to devise a method which will enable such stockings to be made without enlarging the knitting in order to form the pockets of the heel and consequently without necessitating special frames and specially trained operators.

The method according to this invention consists in forming on the knitting frame the rough blank of the stocking in the known manner, in reinforcing the rough blank at the part corresponding to the heel while leaving at this region on the frame the same width of knitting for the heel, and then in subjecting the stocking to a finishing treatment, that is to say by ironing the stocking held on a former, i. e. by moistening, steaming and heating it, the reinforced region corresponding to the heel then taking up its definite shape.

The method of manufacture and the articles thereby obtained present in addition the features which appear from the appended claims and the following description with reference to the annexed drawings, in which Fig. 1 shows a flat rough blank of a stocking made in accordance with the new method; Fig. 2 shows the reinforced regions on an enlarged scale; Fig. 3 shows the stocking placed on a former; Fig. 4 shows a portion of the leg and the foot of the final stocking; Figs. 5 and 6 show tubular rough blanks of a stocking.

In order to carry out the process according to the invention and to form a knitted article, such as a stocking, a flat rough blank is knitted on a rectilinear frame, the said rough blank presenting regions reinforced by knitting, particularly in the region of the heel.

For this purpose (Figure 1) the rough blank 40 is knitted in such a way as to form the length of the stocking commencing at the top while effecting only the usual contractions on the frame which are represented by dotted lines in Figure 1; the frame used is consequently a normal mechanism without any complication and necessitates neither any particular attention nor difficult operation.

In the portion corresponding to the heel the lateral regions 11¹ and 11² are reinforced by an operation termed strengthening, that is to say by knitting an auxiliary thread which is superposed on the principal thread of the knitting.

In this way there is obtained a rough blank presenting reinforced lateral regions the contour 55 of which is represented by the lines 12¹, 12²;

these regions do not comprise any special widened part for the position of the heel.

The reinforced regions 11¹, 11² may also be formed by an operation termed "split fashioning"; for this purpose the knitting is effected 5 with two threads of different sizes, viz. a thin ordinary thread, for example of silk, constituting the length of the stocking and a thicker thread constituting the reinforced regions 11¹, 11² of this stocking.

In this operation the two threads (thick thread and thin thread) are superposed on one or a few needles only of the knitted article in order to connect its different parts together as shown at 16' on Figure 2.

In any case the flat rough blank obtained is folded along its line of symmetry and is sewn along its two superposed edges.

The finishing off operation is then proceeded with.

For this purpose the stocking is threaded on a former 13 (Figure 3), the heel 11 of the former straining the meshes of the reinforced regions 11¹, 11² and compelling them to arrange their contour in the form of a pocket.

The former with the stocking fitted thereon is subjected to a moistening, vaporizing and heating treatment in such a way that the meshes become expanded, the foot of the stocking and in particular the reinforced heel then taking up the 30 definite contour of the former.

The stocking finally obtained retains a suitable contour permitting it to take up perfectly the shape of the leg and the foot as is shown in Figure 4.

Figs. 3 and 4 show in particular that the reinforced region of the knitted article comprises firstly two lateral regions 11¹ and 11², corresponding to the upper heel and the heel proper, and then a region 14¹, 14², corresponding to the 40 toes of the foot, the said two regions 11¹, 11², on the one hand, and 14¹, 14², on the other hand, being connected to one another by an intermediate region with an elongated curve 12¹, 12², provided in the region below the foot.

Due to this arrangement, after the completion of the reinforced knitting of the region 11¹, 11² corresponding to the heel it is possible to resume the knitting of this reinforcement by progressive increases of the reinforced contours up to the 50 toes of the foot.

On the rough blank of Figure 1 this increase in the contours of the reinforced regions is resumed from the points 17¹, 17² up to the toes of the foot 14. The points 17¹, 17² where this 55

increase commences are also visible on the finished stocking (Figure 4).

According to a modification of the invention the knitted article such, as a stocking, is manufactured on a circular frame, the regions corresponding to the heel being reinforced during the making of the tubular stocking by an operation of strengthening or an operation termed "split fashioning" without proceeding to the well-known widening operation obtained by alternate knitting with only half of the needles.

The stocking thus knitted (Figures 5 and 6) presents reinforced regions 15 corresponding to the heel. The second operation is then proceeded with, which consists in finishing off the stocking by engaging it on a former while folding it along the plane ABCD (Figures 5 and 6) and subjecting it to moistening, vaporizing and heating treatments.

20 The method according to this invention enables the following knitted articles to be produced:—

(a) A flat rough blank (Figure 1 or 2) presenting no widened portion and presenting on 25 the other hand a reinforcement in the region corresponding to the heel;

(b) A tubular rough blank (Figures 5 and 6) presenting in the region corresponding to the heel a continuity of the meshes without any 30 widened portion and a suitable reinforcement;

(c) Stockings with reinforced heels and having shapes obtained without any widened portion by a suitable reinforcement of certain parts of the stocking during the knitting and by a finishing operation.

I claim:—

1. The method of manufacturing knitted articles such as stockings comprising forming on the frame a rough blank in the known manner, reinforcing the rough blank at the region corresponding to the heel, while leaving at this region on the frame the same width of knitting for the heel, and then subjecting the stocking to a finishing treatment, by ironing the stocking while 40 held on a former i. e. moistening, steaming and heating it, the reinforced region corresponding to the heel then assuming its definite shape.

2. The method of manufacturing knitted articles such as stockings comprising forming on the frame a rough blank in the known manner, knitting in the region corresponding to the heel an auxiliary thread which is superposed on the principal knitting thread while leaving at said 50 region on the frame the same width of knitting, and then subjecting the stocking to a finishing

treatment, by ironing the stocking while held on a former i. e. moistening, steaming and heating it, the reinforced region corresponding to the heel then assuming its definite shape.

3. The method of manufacturing knitted articles such as stockings comprising forming on the frame a rough blank in the known manner, knitting the region corresponding to the heel by means of a stronger thread than that used in the other parts, while leaving at said region 10 on the frame the same width of knitting, superposing the thick thread and thin thread on only one or a few needles in order to connect the reinforced region to the other portions and then subjecting the stocking to a finishing treatment, 15 by ironing the stocking while held on a former, i. e. moistening, steaming and heating it, the reinforced region corresponding to the heel then assuming its definite shape.

4. The method of manufacturing knitted stockings comprising forming a flat rough blank on a rectilinear frame, reinforcing the rough blank at the region corresponding to the heel while leaving at said region on the frame the same width of knitting for the heel, and then subjecting said stocking to a finishing treatment, by ironing the stocking while held on a former i. e. moistening, steaming and heating it, the reinforced region corresponding to the heel then 20 assuming its definite shape.

5. The method of manufacturing knitted stockings comprising forming a tubular rough blank on a circular frame, reinforcing the rough blank at the region corresponding to the heel while leaving at said region on the frame the same width of knitting for the heel, and then subjecting the stocking to a finishing treatment, by ironing the stocking while held on a former i. e. moistening, steaming and heating it, the reinforced region corresponding to the heel then 25 assuming its definite shape.

6. The method of manufacturing knitted articles, such as stockings, comprising forming on the frame a rough blank in the known manner, successively reinforcing on said blank firstly 45 a region corresponding to the heel while leaving at that region on the frame the same width of knitting, then an intermediate region with an elongated curve, finally a region corresponding to the toe of the foot, and then subjecting the 50 stocking to a treatment by ironing the stocking while held on a former after having moistened, steamed and heated it, the reinforced regions thereby assuming their definite shape.
